APPARATUS FOR MAKING CAST BODIES
WITH INSERTED COILS

Arthur T. Richardson and Warren A. Smith,
Geneva, Ill., assignors to Smith & Richardson
Manufacturing Company, Geneva, Ill., a corpo-
ration of Illinois

Application October 21, 1944, Serial No. 559,868

2 Claims. (Cl. 22—125)

1

The invention relates to the formation of female screw-threads in metal castings.

When screw-threads are formed in aluminum or other soft metals the screw-thread of a tapped hole has a tendency to seize or become embedded in any irregularity or rough spots present on the male screw inserted in the hole, and in many instances in tightening or unscrewing the male screw the female threads are torn out of the parent metal or irreparably damaged. To overcome these objections to tapped holes it has been proposed to cast a helical coil of wire of the desired physical strength or hardness in elements formed of soft metal to form female screw-threads in said elements.

One object of the invention is to provide a composite element with a helical coil of wire of the desired physical properties and having a cross-sectional shape conforming to the thread of a mating male screw embedded in the cast metal and securely enclosed therein against displacement by stresses applied to the female thread by the mating screw.

Another object of the invention is to provide improved means and a method for use in expediting the fabrication of elements composed of wire coils and cast metals by which the composite elements can be accurately produced and at a low cost.

Another object of the invention is to provide improved means and a method for casting coil inserts in elements provided with ribs or lugs.

Other objects of the invention will appear from the detailed description.

The invention consists in the several novel features hereinafter set forth and more particularly defined by claims at the conclusion hereof.

In the drawings:

Fig. 1 is a side elevation of a mandrel used in casting the wire forming the screw-thread in elements formed of cast metal.

Fig. 2 is an elevation of the mandrel with a coil of wire thereon for use in casting the coil in the element, and positioned in a pattern and sand mold.

Fig. 3 is a plan of the coil of wire used for forming the female screw-thread in the casting.

Fig. 4 is a section of the mandrel with the coil of wire for forming the female thread in the mold after the pattern has been removed and before the metal has been poured into the mold and around the coil.

Fig. 5 is a section illustrating a completed element with the coil of wire forming the female screw-thread and embedded in the cast metal.

2

Fig. 6 is a section of an assembled face-plate mandrel and coil of wire around the mandrel and held in a pattern for embedding the coil of wire in a cast rib or lug.

Fig. 7 is a section of a fabricated element including a coil of wire forming a screw-threaded opening in a cast lug or rib, and a face-plate.

Fig. 8 is a side elevation of the parts shown in Fig. 7.

In carrying out the invention a female screw-thread is formed in a casting 12 by a coil of wire, the inner periphery of which is V-shaped in cross-section to conform to the thread of the male screw to be used with the female thread. Preferably this wire is rectangular in cross section with V-shaped outer sides which are embedded in cast metal. The wire coil is formed of metal having the desired physical properties for strength and wear, and preformed into a helical coil 10. Each end of the coil 10 is extended radially outwardly and reverted to form an outer coil 11 of several convolutions which surrounds the coil 10 to provide adequate portions for a rigid anchoring effect of the wire in the casting 12. Preferably the wire is twisted about 90° between the inner coil 10 and the outer coil 11, and the outer coil has one of its four sides wound around the inner coil, as illustrated in Figs. 2, 3 and 5.

In fabricating elements with the wire-coil embedded in the cast metal 12 of the element, the coil 10 is supported on the stem 14 of the mandrel 13. This stem is provided with a screw-thread 14a which conforms to the inner periphery of the wire-coil 10 so that the coil can be screwed onto the stem with a fit which will prevent molten metal from flowing in the hole bounded by the inner periphery of coil 10. The mandrel is also used to support the wire-coil in the mold. The upper end of the mandrel has a polygonal head 17

whereby it may be turned for screwing the coil onto and off the stem 14. The mandrel is adapted to be supported with the coil thereon, by the sand rammed in one of the sections of the mold. A collar 15 is screw-threaded to the stem 14 of the mandrel and seated against a shoulder 16 on said stem. Collar 15 has a flange 22 which is adapted to rest on the exposed face of a pattern 20 in a section 21 of the mold to support the mandrel and the wire-coil thereon, while sand is rammed in the other section 24 of the mold and around the upper portion of the mandrel so that the coil will be supported in mold section 24 after the pattern 20 has been removed from the other section 21 of the mold.

In practice it has been found important to

anchor the end portions of the wire-coil in the cast metal so that when a male screw is manipulated in the wire-coil embedded in the cast metal, and the male screw is started into or being removed from the first or second convolutions of the coil, the concentrated stresses on said convolutions will not displace them from the cast metal. For this purpose one end of the coil terminates a sufficient distance below the face of the casting engaged by the male screw so that some of the cast metal is caused to flow between the end convolution of the coil and said face. This spacing of the end convolution of the coil from the working face of the element and flowing of metal between the end face of the coil and said working face and formed by the annular rib or extension 18, causes the cast metal to reinforce the end-convolution of the wire coil against displacement from the cast metal. Rib 18 has a downwardly tapered periphery which extends into the mold cavity 25 so that the collar can be withdrawn from the cast metal. By this means the convolutions at the end of coil 10 are securely anchored in and reinforced by the cast metal to prevent them from being pulled out or stripped from the cast metal by the male screw.

In making the composite element, the coil 10 is screwed onto the stem 14 of the mandrel 13 with its upper end against the annular rib 18 on the collar 15. Sand is rammed in the mold-section 21 around the pattern 20 which is provided with a cavity 23 for receiving the wire-coil 10. The stem of the mandrel and the wire-coil are inserted into the recess 23 in the pattern as illustrated in Fig. 2. The flange 22 of collar 15 is placed on the upper face of the pattern 20 so that the mandrel and wire-coil will be supported by the pattern. Sand is then rammed into the mold section 24 and around the upper portion of the mandrel and around the collar. The mold sections are then parted and the pattern 20 removed from section 21, as illustrated in Fig. 4, while the mandrel and wire-coil are supported from the rammed sand in mold-section 24. Metal is then poured into the cavity 25 between the mold sections so it will flow around the wire-coil and the annular rib 18 of the collar 15, and between the upper end convolution of coil 10 and the flange 22 of collar 15. The mold sections are then parted and the mandrel with collar 15 thereon is unscrewed from the wire coil so that the composite element illustrated in Fig. 5 will be formed. This exemplifies a composite article which comprises a wire-coil of suitable metal embedded in a body of cast metal and in which the end of the coil is spaced from and securely anchored in the cast metal to prevent the coil from being stripped from or pulled out of the casting by screw pressure from an inserted screw. The coil extensions 11 supplement this anchoring effect of the coil in the casting.

Figs. 6, 7 and 8 exemplify a modification of the invention for producing threaded openings in the ribs or lugs of a cast body or element, in connection with a face plate extending around the lugs or ribs. The body 12^a is provided with a rib or lug 12^b. A sheet metal plate 28 has sides and an end fitting around the sides and end of the rib or lug 12^b to form a facing or reinforcement around the hole through the rib. A coil of wire 10^a, diamond shaped in cross section, has integral convolutions 11^a surrounding the end portions of the coil 10^a, and is embedded in the cast metal lug or rib 12^b on the body 12^a. In fabricating this form of the invention, the wire-coil is sup-

ported by a bolt 30 which functions as a mandrel and comprises a stem 32 provided with a screw-thread conforming to the inner periphery of coil 10^a, a head on one end of the stem 32 and a nut 33 threaded to the other end of said stem. The stem of this mandrel or bolt is adapted to extend through the opening to be formed in the rib 12^b and through openings 34 in the sides of plate 28. Nut 33 is provided with a cylindrical inward extension 37 which fits in and extends through the opening 34 in one side of plate 28. A cylindrical portion 36 is provided on the bolt 30 adjacent head 31 and extends through and fits in the opening 34 in the other side of face plate 28. 10 These cylindrical extensions or portions extend inwardly to the outer ends of the wire-coil which are spaced inwardly from the sides of the face plate, respectively, to cause some of the molten metal to flow between the outermost convolutions 20 of the coil and the inner faces of the sides of the face plate to provide cast metal reinforcement for said convolutions. The assembled plate 28, wire-coil 10^a and mandrel-bolt 30 are placed in a pattern 40 which is shaped to form the body 12^a with a rib or lug 12^b thereon, and provided with an open ended recess 41 for receiving the wire coil 10^a, as illustrated in Fig. 6. Sand is rammed into a two-part mold around the pattern 40 and the head and nut on the bolt 30 and around the face plate. The mold is then parted and the pattern 40 is withdrawn from one section of the mold while the mandrel-bolt 30, wire-coil 10^a and face plate 28 are retained in the rammed sand of the other section of the mold. The rammed mold sections are then reassembled and molten metal is poured into the cavity left by the pattern. The metal will flow to form the body or element with the rib or lug 12^b thereon, around the wire-coil, fill the space between the ends of 35 the coil and the face plate, and some of the metal will flow between the end-convolutions of the wire-coil and the sides of the face-plate 28. When the metal has set, the mold will be parted and nut 33 unscrewed from the stem 32 of bolt 40 45 30. The bolt can then be unscrewed from the wire-coil embedded in the cast metal. The face plate, coil and the cast body will then be joined together, as illustrated in Figs. 7 and 8. The portions of the cast metal between the end convolutions of the wire-coil and the sides of plate 28 will reinforce said convolutions against displacement and the ends of the coil will be securely anchored in the cast metal.

The invention exemplifies a composite element 55 comprising a cast metal body with a thread-forming coil of suitable metal securely anchored in the cast metal so that the ends of the coil cannot be stripped from the cast metal and in which the coil is solidly anchored in the cast metal 60 against displacement by screw pressure concentrated at the ends of the coil. The invention also exemplifies simple and efficient means for use in fabricating elements with wire-coil inserts.

The invention is not to be understood as restricted to the details set forth since these may be modified within the scope of the appended claims without departing from the spirit and scope of the invention.

Having thus described the invention, what we 70 claim as new and desire to secure by Letters Patent is:

1. A pattern and flask assembly for a mold for casting screw-thread-forming wire coils in cast metal bodies, comprising: a mould including upper 75 and lower flask sections for sand, a pattern in

the lower flask section provided with a face at the parting line of the mould, and with a downwardly extending recess in said face, a mandrel provided with a screw thread extending into the recess, a wire-coil screwed on the thread of and separable from the mandrel, in, and spaced from the side of the recess in the pattern, and having its ends terminating in said recess, an annular abutment on the mandrel engaging said face of the pattern for supporting the mandrel with the wire coil thereon in the recess, an upwardly extending stem on the mandrel around which the sand may be interfittingly packed for securing the mandrel in the upper flask section when it is separated from the pattern means on the mandrel extending into the recess to meet the upper end of the coil, and of less diameter than the outer diameter of the coil, for forming an annular pocket in the mold for casting metal between the lower face of the collar and the upper end of the coil when the pattern is removed from the mold.

2. A pattern and flask assembly for a mold for casting screw-thread-forming wire coils in cast metal bodies, comprising: a mould including upper and lower flask sections for sand, a pattern in the lower flask section provided with a face at the parting line of the mould, provided with a downwardly extending recess in said face, a mandrel provided with a screw thread extending into the recess, a wire coil screwed on the thread of the mandrel in, and spaced from the side of, the recess in the pattern and having its upper end terminating below said face of the pattern, a collar detachably held on the mandrel engaging said face of the pattern, for supporting the mandrel with the wire coil thereon in the recess, means

5 on the mandrel around which the sand may be interfittingly packed for securing the mandrel in the upper flask section, when it is separated from the pattern, an annular member on the collar, extending into the recess to meet the upper end of the coil, and of less diameter than the outer diameter of the coil, for forming an annular pocket in the mold for casting metal between the lower face of the collar and the upper end of the coil when the pattern is removed from the mold.
